CLAIM

The ornamental design for a vertical hydroponics system, as shown and described.

DESCRIPTION

FIG. 1 is a front perspective view of a vertical hydroponics system.

FIG. 2 is a front elevation view.

FIG. 3 is a rear elevation view.

FIG. 4 is a right-side view.

FIG. 5 is a left-side view.

FIG. 6 is a top view; and,

FIG. 7 is a bottom view.

The broken line showing of the hydroponics system is included for the purpose of showing portions of the article and forms no part of the claimed design.
